(57) **CLAIM**

The ornamental design for a hand support, as shown and described.

DESCRIPTION

FIG. 1 is a top perspective view of a hand support showing our new design;

FIG. 2 is another top perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a right side elevational view thereof, the left side being a mirror image; and,

FIG. 8 is a right side sectional view thereof taken along lines 8-8 of FIG. 3.

The broken line representation of a hand in FIG. 1 and the broken line representation of a portion of the base shown in FIG. 4 form no part of the claimed design.

1 Claim, 4 Drawing Sheets

FIG. 3
